UNITED STATES PATENT OFFICE.

LÉON PIERRE DAZUN, OF BREAUX BRIDGE, LOUISIANA.

DESIGN FOR AN EATING-FORK.

SPECIFICATION forming part of Design No. 25,384, dated April 14, 1896.

Application filed November 30, 1895. Serial No. 570,705. Term of patent 14 years.

To all whom it may concern:

Be it known that I LÉON PIERRE DAZUN, a citizen of the United States, residing at Breaux Bridge, in the parish of St. Martin 5 and State of Louisiana, have invented a new and original Design for Forks, of which the following is a specification.

This invention relates to a new and original design for eating-forks; and it has for its 10 object to provide a design of this character that shall be both useful and ornamental.

The leading feature of the design resides in a fork having a twisted shank provided at one end with a circularly-shaped figure and 15 at its other end with three substantially parallel round branches, all of which branches have a uniform slight longitudinal curvature from end to end and have their point extremities disposed approximately in transverse 20 alignment, the central one of said branches being provided at said point extremity with a flattened triangularly-shaped figure.

In the drawings, Figure 1 is a perspective view of a fork embodying the herein-described 25 design. Fig. 2 is a plan view thereof.

Referring to the accompanying drawings, the numeral 1 designates an eating-fork having a twisted shank 2 provided at one end with a circular figure 3, and at its other end with three substantially parallel round branches 4, 30 all of which branches have a uniform slight longitudinal curvature from end to end and have their point extremities disposed in approximately transverse alignment, the central one of the three branches 4 being provided at its point extremity or tip end with a flattened triangularly-shaped figure 5.

What is claimed is—

The design for an eating-fork herein shown and described. 40

In testimony that I claim the foregoing as my own I have hereto affixed my signature in the presence of two witnesses.

LÉON PIERRE DAZUN.
